UNITED STATES PATENT OFFICE

2,070,728

PORTABLE HUMIDIFIER

Hugo H. Hanft, St. Paul, Minn.

Application February 23, 1934, Serial No. 712,472

1 Claim. (Cl. 261—88)

It is the object of this invention to provide a novel and unusually efficient mechanism for moistening air.

A further object is to provide a portable device whereby moisture-laden air is delivered free of water particles of appreciable size.

Other objects will appear and be more fully pointed out in the following specification and claim.

10 Referring to the accompanying drawing which illustrates the best form of my device at present known to me:

Figure 1 is a central, vertical section through the outer casing, well and motor support and showing the interior mechanism in side elevation;

Fig. 2 is a horizontal section taken on the line 2—2 of Fig. 1;

Fig. 3 is a plan view of the well and baffle there- 20 in;

Fig. 4 is a plan view of the water pump, and

Fig. 5 is a central, vertical section through the pump and support therefor.

My device is of the portable, self-contained 25 type having a suitable cabinet or outer casing 6 formed with an outlet opening 7 for the moistened air near the top and an inlet opening 8 at the back for air and water. Within the bottom of the casing 6 is a tank 9 for water and extending upwardly from the tank is a large cylindrical well 10, open at its lower end and communicating at its upper end with the outlet opening 7 for air. A vertical shaft 11 is disposed axially in the well 10 and is directly driven by an electric motor 12 in which the shaft has bearings. This motor is supported on a spider having arms 13 and 14 extending substantially radially therefrom and bolted to the front and side walls respectively of the casing 6. The shaft 11 is hollow or tubular 30 from end to end and has fixed thereon above the motor 12 a series of fan blades 15. These blades are spaced apart vertically, in pairs, on the shaft 11. The upper end 16 of the shaft 11 is open to supply water to the surfaces of the fan blades.

45 Operatively connected to the lower end of the shaft 11 is a water pump 17 arranged to draw water from the tank 9 and to deliver it under pressure within the shaft and out through upper, open end 18. Suitable internal construction for 50 the pump 17 is illustrated in Figs. 4 and 5. The casing of the pump has an annular opening 19 adjacent to the shaft 11. Fixed on the shaft 11 within the casing, is a disk 20 and a series of blades 21, upstanding from said disk and extending from the shaft outward. An annular space

between the outer periphery of the disk 19 and the inner surface of the casing allows water to pass from the upper to the lower face of said disk. In operation, water enters the opening 18 and is driven out by centrifugal force on the top 5 of the disk 19, between the blades 20, then down at the outer periphery of the disk 19 and radially inward to the opening in shaft 11 beneath the disk 19.

The well is preferably a sheet metal cylinder 10 supported on rings 21 which clamp its outer surface and have ends bolted to small angle brackets 22 mounted on the sides of the casing 6, as best shown in Fig. 2. The upper end of the well is fitted with an elbow-like conduit 23 to deliver 15 the moistened air laterally through the opening 7. Within the well 10 is fixed a helical baffle 24. This baffle is arranged to make a plurality of turns within the well and the lead or pitch of successive turns diminishes progressively up- 20 wardly so that the stream of air is directed helically and its velocity is somewhat reduced as it passes upward.

Operation

25 In operation, a supply of water is placed in the tank 9 and the motor 12 is operated so that the blades 15 create an upwardly swirling stream of air while water is withdrawn from the tank 9 by the pump 17 and delivered in a stream from the upper end of the shaft 11. The water so delivered flows down upon successive pairs of blades so that the entire surfaces of the blades are moistened. Each of the blades throws an excess of water outward against the walls of the well 10. My arrangement of spaced fans results 30 in the breaking up of the water into minute particles and a thorough distribution of these particles throughout a zone of considerable vertical extent within the well 10, while air admitted 35 through the opening 8 is drawn into the bottom of the well and forced up through this spray zone. Water particles of appreciable size are picked up by the draft of air and carried further up within the portion of the well having the baffle 40 24. This baffle directs the air helically and causes the larger water particles to be deposited on the inner surfaces of the well and baffle while the velocity of air is somewhat reduced. By the time the air passes out through the opening 7 it 45 is substantially saturated but all particles of appreciable or objectionable size have been removed therefrom. Any excess of water, deposited on the surfaces of the mechanism in the vapor zone, 50 flows back into the tank 9.

Where radiators are conveniently located in heated buildings, I recommend placing the humidifier with the back opening 8 adjacent to a radiator so that warm air is supplied to the bottom of the well. Two or more of the units, comprising the well, motor driven fans, pump and baffle may be placed in a single cabinet, side by side, so that such units have a common water supply tank at the bottom. Tests of my device 10 show that a high degree of efficiency is obtained and the moist air is unusually free of the larger spray particles or droplets.

Having described my invention, what I claim as new and desire to protect by Letters Patent is:

15 In a device of the class described, a cylindrical well having an outlet for air at its upper end and

an inlet for air at its lower end, a hollow, axial shaft mounted in said well, means for supplying water under pressure to the lower end of said shaft, a series of vertically spaced fan blades fixed on said shaft within the lower portion of 5 said well, said shaft having an outlet opening for water disposed above the uppermost of said blades to allow flow of water down along the exterior of said shaft to the several blades, a helical baffle fixed in the upper portion of said well in 10 coaxial relation to said shaft, the convolutions of said baffle being widely spaced and having a pitch such that the velocity of the air is not greatly reduced and power-driven means for rotating said shaft.
